TROLLEY POLE BASE CONSTRUCTION

Frank E. Wall, Detroit, Mich., assignor to Gabriel Steel Company, Detroit, Mich., a corporation of Michigan

Application June 23, 1930. Serial No. 463,320

6 Claims. (Cl. 189—28)

The invention relates to metallic poles designed for supporting electric lights, trolley wires, and for similar uses, and has more particular reference to the construction of an ornamental base for supporting such poles. In addition to serving as an intermediate member of pleasing appearance between the footing and the pole proper, such bases are frequently utilized for enclosing electrical equipment used in connection with the lights. In order that this equipment can be installed readily and that access may be had to it from time to time, it is necessary to provide openings provided with doors in the sides of this base.

In the present state of the art, it is usual to form such ornamental bases of cast metal and of a hollow construction provided with removable panels or doors providing access to the chamber within. The base is anchored to a concrete foundation and the pole is bolted to the top of the base.

In the case of poles used for lighting service only, bases made of cast iron are of sufficient strength for this service, but are subject to the objection that they are frequently broken by being struck by passing motor vehicles. The danger of such a collision is not merely the damage due to the direct impact, but is also caused from the falling pole which may seriously injure the passengers of the motor vehicle or passing pedestrians. In the case of poles carrying span wires for the support of overhead trolley wires, etc., cast iron bases can not be used as they do not possess sufficient strength for the heavy stresses which occur at the base of such poles. In these cases, it has been customary to make the base of cast steel. These cast steel bases, while being satisfactory from the standpoint of strength, are considerably more expensive than those made of cast iron.

It is the object of the present invention to obtain a construction which has the requisite strength for any purpose for which the pole is intended and is also of such a character that it cannot be shattered when struck by a passing vehicle. It is also an object to obtain a construction which, while having the strength of a cast steel base, may be manufactured at a considerably smaller expense, and which may be made in a variety of designs, either with or without ornamental features. To this end the invention consists in the construction as herein-after set forth.

In the drawings:

Figure 1 is a perspective view of the base show-

ing one of the closing panels and one of the ornamental corners detached;

Figure 2 is a vertical cross section partly in elevation on line 2—2 of Figure 3.

Figure 3 is a top plan view;

Figure 4 is a bottom plan view; and

Figure 5 is a vertical section in a plane transverse to Figure 2 on line 5—5 of Figure 3 showing one of the detachable panels.

Figure 6 is a section on line 6—6 of Figure 3.

Figure 7 is a section similar to Figure 6 showing a modified construction.

As shown, A is a base plate formed of rolled steel and preferably of polygonal form. The center of this plate is cut away at B to provide

an aperture for the passage of electric wires or cables, and there are also apertures C for the passage of anchor bolts which secure the base to the foundation. D and D' are side plates which extend upward from the base plate A and are secured thereto by electric welding. These plates are fashioned to form opposite sides of the base and to extend around the corners to the sides at right angles thereto. The plates are further strengthened by ribs E shown as T-bars which are welded at intervals to the plate and are also welded at their lower ends to the base plate A. As specifically shown, these ribs are on the opposite sides extending inwardly but where the pole is subjected to diagonal stresses they may be placed at the bevel corners as indicated in Figure 7 at E'. F is a top plate secured to the upper ends of the side plates D and D' by electric welding along the upper edges of said plates. The top plate F is centrally apertured at G and is provided with the apertures H for the passage of bolts for securing the base flange of the trolley pole thereto. As the trolley pole is of the usual standard construction, it is not illustrated.

To produce the desired ornamental appearance the corners of the base are provided with ornamental members I, preferably formed of cast iron and which may be of any desired shape, number or design. These ornamental members at their lower ends rest upon an annular member J which surrounds the lower edge of the base A and which is preferably formed of an angle bar having its upper flange notched to permit bending to the contour of the base. This member J is welded to the base and to the plates D and D' so as to produce the appearance of a heavy block from which the tapering sides and corner members rise. The space between the plates D and D' is closed by detachable panels K which when removed provide access to the interior of the hollow

base. Molding strips L may also be placed between the members I at the lower and upper ends of the plates D and D', and also adjacent to plates L' and L² which extend between the plates D and D' above and below the panels K.

5 A base constructed as above described has a mechanical strength far in excess of that which can be obtained from cast iron. Furthermore, any shock applied thereto will not cause a shattering or sudden failure, but merely a deformation, thereby avoiding danger of the dropping of the pole. The ornamentation being formed by cast members, it is possible to change the design at any time at small expense. Also to facilitate such 10 change the members I are not welded to the structure but are merely secured by tap bolts M which are engaged on the inner side of the plates D and D'. Thus my improved construction is one which is adapted for all of the ordinary uses of metallic 15 poles, is relatively low in cost of manufacture and has the great advantage of insuring safety against the dropping of the pole.

What I claim as my invention is:

1. A base for trolley or light poles comprising 20 a hollow member formed from wrought metal plates or shapes including a base plate, opposite side plates fashioned to extend around the corners and a top plate, the upper and lower ends of said side plates being welded respectively to said base and top plates, and detachable panels 25 extending between said welded side plates and secured thereto.

2. A base for trolley or light poles comprising 30 a hollow member formed from wrought metal plates or shapes including a base plate, opposite side plates extending upward therefrom and fashioned to extend around the corners, a top plate, the ends of said side plates being welded to said bottom and top plates, detachable panels 35 for closing the space between said side plates and ornamental members detachably secured to said side plates.

3. A base for trolley or light poles comprising 40 a hollow member formed from wrought metal plates or shapes including a base plate, opposite 45 plates extending upward therefrom fashioned to extend around the corners, a top plate, the ends of said side plates being welded to said bottom and top plates, detachable panels for closing the space between said side plates and ornamental members detachably secured to said side plates.

side plates extending upward therefrom fashioned to extend around the corners, a top plate, the ends of said side plates being welded to said bottom and top plates, an anchor bar bent about the contour of said base plate and secured thereto and to said side plates to give the appearance of a heavy base block, and ornamental members secured to the corners of said side plates and extending from base to top.

4. A base for trolley or light poles comprising 80 a hollow member formed of wrought metal plates or shapes including a base plate of polygonal form and centrally cut away, opposite side plates rising from said base plate and spaced inwardly from the outer edges thereof, said side plates being fashioned to extend around the corners and having their lower edges welded to said base plate, a top plate welded to the upper edges of said side plates, an angle bar bent about the contour of said base plate and welded thereto, the top flange of said angle extending inward to said side plates and welded thereto, ornamental members formed of cast metal secured to the corner of said side plates and detachable panels 85 for closing the space between said side plates.

5. A base for trolley or light poles comprising 90 a hollow member formed from wrought metal plates or shapes including a base plate, opposite side plates rising therefrom fashioned to extend around the corners, a top plate, said side plates 95 being welded at their upper and lower ends to said top and bottom plates, and reinforcing ribs extending longitudinally of said side plates and welded thereto at intervals, said ribs being welded at their upper and lower ends to said top and 100 bottom plates.

6. A base for trolley or light poles comprising 105 a hollow member having a base and opposite sides formed of wrought metal plates welded to each other, said sides being fashioned to extend 110 around the corners, a top member adapted to support the pole welded to the upper ends of said side plates and detachable panels extending between said side plates and secured thereto.
